UNITED STATES PATENT OFFICE.

HUGO BRISACHER, OF NEW YORK, N. Y., ASSIGNOR OF ONE-HALF TO F. P. DODGE, OF NEW YORK, N. Y.

ELECTRIC SWITCH.

1,192,035.

Specification of Letters Patent. Patented July 25, 1916.

Application filed January 13, 1915. Serial No. 1,933.

To all whom it may concern:

Be it known that I, Hugo BRISACHER, a citizen of the Republic of Switzerland, and a resident of the borough of Manhattan, city, county, and State of New York, have invented a new and useful Improvement in Electric Switches, of which the following is a specification.

My invention relates to improvements in electric switches and has particular application in connection with the well known type of "knife-blade" switches.

The object of the invention is to assure a perfect electrical contact and the object of the invention is accomplished broadly by providing means for causing a spring engagement between the blade and the contact jaws or clips.

In the following is described, in connection with the accompanying drawings, one form of device embodying my invention, the features thereof being more particularly pointed out hereinafter in the claims.

In the said drawings Figure 1 is a side elevation of an electric switch of the knife-blade type showing one form of my invention in connection therewith. Fig. 2 is a plan view of the device shown in Fig. 1, parts being broken away.

Similar numerals of reference indicate similar parts throughout the several views.

As illustrated 1 indicates a base of slate or other suitable insulating material to which contact blocks 2 and 3 are secured in any suitable manner. Line wire terminals 4 and 5 are secured to blocks 2 and 3 respectively in any suitable manner so as to assure good electrical contact.

6, 6 indicate a pair of contact clips mounted on block 2 in which blade 7 is hingedly mounted on a suitable pin 8.

9, 9 indicate a pair of contact clips mounted on block 3 and adapted to form a jaw for the reception of blade 7. Clips 9 are vertically slit so as to form a central spring leaf 10 and side leaves 11, 11, the tops of the respective clips being sprung outward slightly away from each other so as to normally form a general V-shaped jaw 50 for the reception of the blade.

12, 12 indicate spring pieces, preferably of hard drawn copper, riveted or otherwise firmly secured to blade 7, and normally inclined at their free ends slightly toward the blade. Spring pieces 12, 12, are narrower

than the blade where they are adapted to contact with clips 9, 9, and consequently, in closing and opening the switch, the blade alone makes and breaks contact. In other words the blade enters the contact clips first followed by the two spring pieces 12, 12 which latter overlap the clips 9, 9, producing an outside or independent pressure against the clips thus forcing the contact clips tightly against the blade and assuring an absolutely perfect contact. When closed the blade is between the clips tending to force them apart and the spring pieces 12, 12 are at either side of the clips tending to force them inward against the blade, the clips and the blade being thus held together under spring engagement. As shown, said spring pieces 12, 12 are preferably fixed at one end and in electrical contact with the blade 7, the other end being free, and further provided with a flattened portion adapted to make electrical engagement with the flattened face of the contact clips; said flattened portion is usually adjacent the free end and may be provided with a circular or other indentation pressed therein to secure rigidity of said flattened portion.

The invention may be applied to double as well as single throw switches and in fact finds use in any suitable type of switch device wherein the principles of the invention may be applied.

I do not restrict myself either to the details of construction illustrated or to the general arrangement as described, further than the scope of the appended claims demands.

I claim:

1. The combination of a resilient contact having opposite contact faces, a switch blade slidably engaging one of said faces when said switch blade is in its closed position, and an arm connected at its one end directly to said switch blade and having its other end free, the portion of said arm adjacent said free end slidably engaging the other of said faces of the resilient contact, when said switch blade is in its closed position, said arm portion extending longitudinally of said switch blade and having its circuit breaking edge advanced relative to the circuit breaking edge of said switch blade.

2. The combination of a pair of substantially vertically extending, side by side, resilient contacts, a switch blade pivoted to

move in a substantially vertical plane and adapted to slidably engage one face of each said contacts, oppositely disposed arms of resilient conducting material each having one end fixed to and centrally of said blade and its other end free and respectively slidably engaging said contacts on a face opposite to said one face thereof when said blade is moved to closed position, said arms 10 at their respective free end portions having a width less than the width of said blade.

3. The combination of a switch blade, a flat contact adapted to be slidably engaged on one face thereof by said blade, and an

auxiliary contact having one end fixed to 15 and electrically connected with said blade and having its other end free, said auxiliary contact having a flat portion intermediate its ends and provided with an indentation for stiffening said flattened portion.

In testimony whereof I have signed this specification in the presence of two subscribing witnesses.

HUGO BRISACHER.
